UNITED STATES PATENT OFFICE.

JAMES W. MACNAMARA, OF BLAIRSVILLE, PENNSYLVANIA.

DESIGN FOR A FLAG.

SPECIFICATION forming part of Design No. 21,788, dated August 23, 1892.

Application filed July 2, 1892. Serial No. 438,832. Term of patent 7 years.

To all whom it may concern:

Be it known that I, JAMES W. MACNAMARA, a citizen of the United States, residing at Blairsville, in the county of Indiana and State 5 of Pennsylvania, have invented a new and original Design for Flags, of which the following is a specification.

The invention relates to a new and original design for flags.

10 The object of the present invention is to provide an ornamental, attractive, and symbolic flag for use of societies or the like; and the essential features reside in a flag having stripes and a square or rectangular field bearing a representation of the sun and its rays 15 and a curved line of stars.

The figure of the drawing represents a flag, showing my new design.

Like numerals of reference indicate corresponding parts in the drawing.

1 designates a flag having seven stripes 2 and provided at its upper corner with a rectangular field 3, bearing a representation 4 of the sun and having rays 5. On the field below the sun and its rays is arranged a curved 25 line of twelve stars, (designated by 6.)

What I claim is—

The design for a flag, herein shown and described.

In testimony that I claim the foregoing as 30 my own I have hereto affixed my signature in the presence of two witnesses.

JAMES W. MACNAMARA.
